(57) CLAIM

The ornamental design for a decorative sexual sculpture, as shown and described.

DESCRIPTION

FIG. 1 is a top plan view of a decorative sexual sculpture showing our new design;

FIG. 2 is a front elevational view of a decorative sexual sculpture showing our new design;

FIG. 3 is a rear elevational view thereof;

FIG. 4 is a bottom plan view thereof;

FIG. 5 is a side elevational view taken from the left of FIG. 2; and,

FIG. 6 is a side elevational view taken from the right of FIG. 2.

The broken lines showing in FIGS. 1, 2, 3, 4, 5 and 6 are for illustrative purposes only and form no part of the claimed design.
